UNITED STATES PATENT OFFICE.

FRANK H. HOBERG, OF GREEN BAY, WISCONSIN.

FEEDING-CABINET.

1,176,143.

Specification of Letters Patent. Patented Mar. 21, 1916.

Application filed October 19, 1914. Serial No. 867,274.

To all whom it may concern:

Be it known that I, FRANK H. HOBERG, a citizen of the United States, residing at Green Bay, county of Brown, and State of Wisconsin, have invented new and useful Improvements in Feeding-Cabinets, of which the following is a specification.

My invention relates to improvements in feeding cabinets for rolled paper packages of that type in which the lower end of the cabinet is open and sheets of paper are permitted to drop and hang through the opening, whereby the sheets may be successively grasped and torn off from the remainder of the package.

In a former application filed by me April 17th, 1914, Serial No. 832,415, I have shown and described a roller, having a frictional bearing surface, and supported by a reciprocating carrier, said roller being free to rotate in one direction only and the carrier being reciprocated to cause the roller to move forwardly, engage the sheet and push or draw it backwardly until the end of the sheet is delivered from the top of the package and permitted to hang in a position where it can be grasped and torn off.

The object of the present invention is to provide means for utilizing a brush for the purpose of frictionally discharging the sheets.

In the drawings—Figure 1 is a transverse sectional view of a paper cabinet embodying my invention, showing a roll of paper therein. Fig. 2 is a longitudinal sectional view of the same, showing the roll and feeding apparatus in elevation. Fig. 3 is a detail perspective view of the frictional paper feeding member. Fig. 4 is a detail side view of a modified form of brush.

Like parts are identified by the same reference numerals throughout the several views.

The cabinet walls preferably comprise a back wall A, end walls B and a cover wall C. The latter forms the front and top of the cabinet. It is hinged to the end walls B at b. The package D is wound upon a core E, which is supported from the cabinet in any suitable manner by a holding plate F. The plate F preferably extends through a slit in the core E, a portion f of the plate being partially severed and offset to pass through the slit. This plate is therefore adapted to prevent the package from rotating upon its support. But the present in-

vention is not dependent upon any specific means for supporting the roll of paper and these features therefore require no further description. The package D illustrated in the drawings is partially severed at G, G', near the upper end of the front side. The outer sheet d of the package is permitted to hang through the open bottom of the cabinet as shown, whereby it may be grasped and removed by tearing it across the tongues g, thus severing it from the next succeeding sheet. When the first sheet is torn away, the upper end of the succeeding sheet might drop and hang by gravity in substantially the position occupied by the first sheet d, but owing to the fact that this upper end partially over-laps the top of the package and also owing to its frictional adhesion to the sheet beneath it, the dropping of the free end cannot be relied upon. It is also undesirable that it should drop automatically for the reason that the paper might then be too easily withdrawn and waste or theft would be facilitated. I therefore provide a frictional bearing member in the upper portion of the cabinet, which consists of a brush pivotally connected with an actuating member in the rear of the package.

The brush is preferably composed of short pieces of wire H, secured to a suitable back, and having a half elbow at h, with the free ends of the wire projecting in the direction in which the sheet is to be discharged. I do not limit the scope of my invention to wires or bristles,

which are intermediately bent, nor to the feature of having any portion thereof in an angular position. It is obvious that the wires or bristles may project angularly directly from the back of the brush if so desired, as shown in Fig. 4. These free ends of the wire or bristles of the brush rest upon the outer sheet and support the brush from the roll of paper. The back of the brush preferably comprises a flexible portion H' in which the wires or bristles are embedded and secured, and also a rigid metal back H'', formed with side flanges h', which are bent inwardly and engage the margins of the flexible backing H', as clearly shown in Fig. 3.

This metal back H'' is provided with a projecting arm I at one end, which is loosely engaged with a crank J at J', said crank constituting a part of a crank shaft K, which has bearings in the respective ends of the cabinet. With this construction it is obvious that a rotation of the crank shaft

will cause the brush to reciprocate upon the surface of the paper.

Near one end of the crank shaft K, it is provided with a pinion L, the teeth of which mesh with the teeth of the toothed segment M, pivoted to one end wall of the cabinet at M' and adapted to be actuated in one direction by a handle N, connected with an arm O of the segment by a cord or other flexible connection P. A coiled spring Q has one end secured to the segment and the other end to the end wall of the cabinet in a position to retract the segment after it has been manually actuated by pulling upon the handle or knob N. When the operator pulls downwardly upon the handle or knob, the brush will be reciprocated upon the surface of the paper adjacent to or across the line of the slits G, G', the bristles or wires projecting angularly in a direction to engage and pull the paper away from the slit at that side occupied by the free end of the succeeding sheet after the preceding sheet has been torn off. The free end of the succeeding sheet will therefore be drawn away from the surface of the roll and discharged to a hanging position below the cabinet. It will therefore be understood that the device operates in a manner quite similar to the discharging device shown and described in said former application, but the brush constitutes the immediate agency for discharging the sheets. Owing to the angular position of the paper engaging portion of the wires or bristles, the brush moves over the paper in one direction without forcibly engaging it, since the points of the wires or bristles will yield freely under such conditions when subject to slight resistance. But when moved in the opposite direction, these points tend to enter the paper, and this tendency may be increased or diminished by changing the weight of the brush.

In Fig. 4 the brush is composed of short bristles, secured to the back preferably in an angular position.

Copies of this patent may be obtained for five cents each, by addressing the "Commissioner of Patents, Washington, D. C."

I claim—

1. A paper feeding device including a brush provided with flexible bristle shaped projections, in combination with means for reciprocating the same upon the surface of a package of paper; said projections being inclined in the direction in which the paper is to be fed.

2. A paper feeding device, including the combination with an open bottomed cabinet, and means for supporting rolled packages of paper therein, of a support, a brush having swinging connection with said support and adapted to bear upon the upper surface of a roll of paper, said brush having flexible inclined bristle shaped projections, and means for actuating the support to reciprocate the brush.

3. A sheet starting device for that class of rolled packages of paper in which the strip is slitted or perforated in the upper portion of the roll to form sheets which successively hang in a position to be torn off, comprising a brush provided with means for pivotally swinging the same from one end, in combination with means for reciprocating the brush upon the package transversely to the axis thereof.

4. A sheet starting device for partially slotted rolls of paper, comprising the combination of a paper roll support, a shaft mounted thereon and provided with a pinion and a crank, a brush pivotally connected with the crank and adapted to rest upon the roll, a segment pivoted to the support and operatively connected with the pinion, a spring for actuating the segment in one direction, and a manually operable handle for actuating it in the other direction.

In testimony whereof I affix my signature in the presence of two witnesses.

FRANK H. HOBERG.
